SHEET 2 OF 2

COMBINATION SOLE-PRESSING AND ACTIVATING APPARATUS

BACKGROUND OF THE INVENTION

In the art of shoe making, it is very common to employ apparatus adjunctive to sole-pressing machines for the purpose of activating adhesive which has been preapplied to the bottoms of lasted uppers and/or to the soles which are to be attached thereto. Such apparatus comprises in its rudimentary form a heated box into which the shoe parts are thrust and remain until used and may hold a single part of a plurality of parts. More sophisticated apparatus for the purpose provides for timing the heating and for supplying the conditioned parts at intervals corresponding to the intervals between attaching operations. The objects of this invention are to provide apparatus of the latter kind which comprises an improvement thereover, is of relatively simple construction and is readily utilizable without alteration of the circuitry of the sole-pressing machine.

SUMMARY

As herein illustrated, the invention comprises, in combination, a sole-pressing machine having right and left sole-pressing assemblies an activator having right and left sole supports adapted to be moved into and out of operative relation with respect to a heated grid, and a control circuit for synchronizing the operation of the sole press and the activator so that while a sole and lasted upper are being joined on the right-hand station of the press, the sole on the sole support at the left-hand side of the activator is conditioned and a fresh sole is placed on the right-hand support for conditioning and while a sole and lasted upper are being joined on the left-hand station of the press, the sole on the sole support at the right-hand side of the activator is being conditioned and a fresh sole is placed on the sole support at the left-hand side of the activator. More especially, the control embodies a control circuit interconnecting the sole press and activator comprising a starting switch for initiating operation to present the sole on the right-hand sole support to the activator for activation of the adhesive thereon and then retract it therefrom for mounting together with an upper on the right-hand press of the sole-pressing machine, a right-hand treadle for effecting operation of the right-hand press upon which the upper and sole are placed and simultaneously actuating a cycling switch for effecting movement of the left-hand sole support to present a sole on the left-hand sole support to the activator for activation of the adhesive thereon while the right-hand press applies attaching pressure to the sole and upper mounted thereon and then retracts it for mounting together with an upper on the left-hand press, and a left-hand treadle for effecting operation of the left-hand press and simultaneously actuating a cycling switch for effecting movement of the right-hand sole support to present the sole on the right-hand sole support to the activator. Following initiation of the cycling, the successive operations are performed by alternate operation of the right and left treadles of the sole press. According to the invention, the activator comprises a cabinet in which there is mounted a heating grid and supports for soles to be treated there being two supports alternately operable to support a sole in the cabinet adjacent the heating grid for activation of the adhesive thereon and thereafter to withdraw it from the cabinet for mounting together with a lasted upper on the sole press. There is a second heating grid in the cabinet for supporting lasted uppers for activating the adhesive thereon simultaneously with that on the soles. In the preferred form the cabinet has a front opening and the sole supports are mounted within the cabinet for movement from within through the front opening. The sole supports are adjustable heightwise relative to the heating grid. The second heating grid is fixed with respect to the cabinet but has articulated parts adapted to be adjusted relative to each other to conform to the bottom of flat or high-arched shoes. The second grid also embodies independently adjustable heat-

ing units for supplying heat, respectively, to the forepart, arch and heel ends of lasted uppers placed on the grid.

The invention will now be described in greater detail with reference to the accompanying drawings wherein:

- 5 FIG. 1 is an elevation of a two-station sole press and a two-station activator interconnected for synchronous operation;
- 10 FIG. 2 is a perspective of the activator;
- 15 FIG. 3 is a fragmentary elevation of the upper part of the activator; and
- 20 FIG. 4 is a circuit diagram for effecting synchronization of the sole press and activator.
- The sole press herein illustrated is disclosed in U.S. Pat. No. 2,866,987 and comprises a base 10 which supports at each of two stations arranged side by side a pad box 12 upon which an assembly comprising a lasted upper and a sole are adapted to be placed bottom down, and a holdown 14 mounted above the pad box on a post 16 situated between the stations. The pad boxes are arranged to be raised and lowered relative to the holdown 14 to permit placing the assemblies on the pad boxes beneath them and to bring them up into clamping engagement with the holdown whereupon attaching pressure is applied by inflating pad boxes. The station operated in turn by treadles T¹T² respectively. The treadles control valves in a fluid circuit for raising and lowering the pad boxes and/or supplying pressure to the interiors of the pad boxes for the attaching operation. The details of the construction and operation of the aforesaid machine are completely available by reference to the aforesaid patent.
- 25 30 The activator 18 comprises a sheet metal cabinet 20 (FIGS. 1 and 3) of rectangular cross section and has a base 22, vertically disposed, spaced parallel sidewalls 24 and a top wall 26. Within the cabinet near the top there is a horizontally disposed partition 28 which divides the cabinet into an upper chamber 30 having at its bottom the partition 28 and a lower chamber 32 having at its top the partition 28. A pair of sole supporting members 34—34 are mounted in the lower chamber, each comprising a relatively flat tray 36 secured to the upper end of a rod 38 which is telescopically mounted in the upper end of a hollow post 40, the lower end of which is pivotally mounted by means of a pin 42 on a bracket 44 fixed to the base 22. A threaded screw 46 provides for adjusting rod 38 longitudinally within the post 40. The sole supports as thus constructed are adapted to be moved from vertical positions, 40 as shown in dot and dash lines, within the cabinet to lateral positions through a side opening 48, in which position the trays 36—36 are inclined forwardly and downwardly from the cabinet.
- 45 50 Within the cabinet on the underside of the partition 28 there is mounted a heating grid 49 comprised of a plurality of spaced parallel resistance rods which are adapted to provide radiant heat which is directed downwardly by a reflector situated above the rods. By adjusting the heightwise position of the trays 36—36 relative to the heating grid 49, the intensity of the heat applied to soles resting on the trays may be varied according to the kind of adhesive employed and/or the rate of heating desired. To prevent the soles from sliding off the trays a guard 50 is secured to the distal end of each.
- 55 60 Movement of the sole supporting members 34 into and out of the cabinet is provided for by air cylinders 52 pivotally connected by means of pins 54 to brackets 56 secured to the base. Rods 58 extending from the opposite ends of the cylinders are pivotally connected by pins 60 to blocks secured to the posts 40. Operating pressure is supplied to the cylinders 52 by means of conductors 62.
- 65 70 A single tray 64 is mounted in the upper compartment 30 above the partition 28 for supporting lasted uppers for activation of adhesive preapplied thereto. Access to the grid 64 is provided through a top opening 66 and a front opening 68 (FIG. 2). The tray 64 comprises parts 70 and 72 hinged to each other by a pin 73 so as to be adjustable relative to each other to provide on the one hand a substantially flat structure for flat bottom shoes and on the other an angular structure for high heel shoes. Adjustment is effected by extending the hinge

pin 73 at opposite ends through vertical slots 75 in the walls of the cabinet and by threading knobs 77 onto the protruding ends which, by engagement with walls, will hold the hinge pin at a selected heightwise position. The distal ends of the parts are pivotally supported in horizontal slots 79 in the sidewalls to permit the aforesaid adjustment. The parts 70 and 72 are made up of transversely extending, spaced parallel rods and heating grids, of which there are three—76, 77.5 and 78, and are attached to the underside of the grid to provide for selected heating of the heel, shank and forepart areas at the bottom of a lasted upper placed on the grid.

A table 80 is attached to the front wall below the front opening 48 to provide for stacking lasted uppers and soles and below the table there is a control box 82 provided with a panel 84 on which there are mounted switches for effecting operation of the apparatus.

Ordinarily in the use of the sole-pressing machine the operator places an assembly comprising an outsole and lasted upper to which adhesive has just been applied or preapplied and just actuated on the pad boss at the right side of the machine and then depresses the treadle at the right side marked T¹ to apply pressure to the assembly to attach the sole to the upper. While the pressure is being applied to the assembly at the right side of the machine the operator assembles an outsole and lasted upper on the left-hand pad box and then depresses the treadle marked T². The operations are timed so that the attaching operation is consummated in approximately the time required to mount an assembly and so that the operator alternately removes a finished shoe and mounts another assembly in its place while the assembly at the other station is under pressure.

In accordance with this invention, foregoing procedure is expedited by synchronizing operation of the activator 18 with the operation of the sole press 10 so that there will always be pairs of lasted uppers and soles available for mounting in the sole-pressing machine for the attaching operation.

This is achieved herein by means of a control circuit C comprising a heating circuit C¹ and a control circuit C², as shown in FIG. 4, connected to a 220-volt 60-cycle power source by a main switch S. A transformer TR¹ steps the voltage down to the control circuit C² from 220 volts to 110 volts.

In the heating circuit C¹ there are three pairs of resistors r₁, r₂ and r₃, which comprise the grid 49, and three pairs of resistors r₄, r₅ and r₆, which comprise the grid 64. The resistors r₁, r₂ and r₃ are connected in the circuit by contacts R_{c1}, R_{c2} and R_{c3} which are adapted to be closed by energization of a relay R embodied in an input controller INP¹ having an actuating button so labeled on the panel 84 the resistors r₄, r₅ and r₆ are energized by input controllers INP², INP³ and INP⁴ having actuating buttons so labeled on the panel 84. The controllers INP¹, INP², INP³ and INP⁴ are temperature controllers which provide for maintaining a predetermined temperature level in the resistor units and the controls INP¹, INP², INP³ and INP⁴ are individually adjustable to enable selectively heating the resistor units in the tray 64 for the purpose of providing different temperatures at different parts of the grid.

The control circuit C² contains a switch FS¹ which is located below the treadle T² and when closed energizes a relay CR¹ which in turn closes contacts CR1A, CR1B thereby starting a timing motor TM¹ and energizing solenoid valves VS¹ and VS². The valve VS² supplies air to one of the cylinders 52 to move the tray at the right side into the cabinet. When the timing motor TM¹ times out relay CR¹ is deenergized, contacts CR1A and CR1B open and the solenoid valves VS¹ and VS² reverse so that the tray 36 at the right side is moved out of the cabinet. Similarly, switch FS² is located below the treadle T¹ and when closed energizes relay CR² which in turn closes contacts CR2A, CR2B thereby starting a timer motor TM² and energizing solenoid valves VS³ and VS⁴. Valve VS⁴ supplies air to the other cylinder 52 to move the tray 36 at the left side into the cabinet. When the timing motor TM² times out the relay CR² is deenergized, contacts CR2A and CR2B open and the solenoid valves VS³ and VS⁴ reverse so that the tray 36 at the left side is moved out of the cabinet. There are three push-

button switches in the circuit in addition to the switches FS¹ and FS², to wit, PB¹, PB² and PB³.

The switch PB¹ when open disconnects the entire controls circuit C² from the source of power and when opened both trays 36—36 extend forwardly from the interior of the cabinet from the front opening (FIG. 2). To prepare the apparatus for operation the switches INP¹, INP², INP³ and INP⁴ are closed.

To start an operating cycle switch PB² is closed and since switch PB² is in parallel with switch FS¹, it causes the tray 36 at the right side to move into the cabinet. The cycle is initiated in this way rather than by depressing the foot switch T¹ because there are no shoes on the press at this time, and it is undesirable to have the press operate without shoes present thereon. When the timing motor TM¹ times out, the right-hand tray moves out of the activator cabinet whereupon the operator removes the sole from the tray and the mating lasted upper from the tray 64, assembles them on the right-hand press and then depresses the foot treadle T¹. This initiates operation of the right-hand press and simultaneously closes switch FS¹ which causes the tray 36 at the left side to move into the cabinet. While waiting for the adhesive to become activated, the operator places a fresh sole and lasted upper on the right tray 32 and right side of the tray 64 respectively. When the timer motor T² times out, the left-hand tray 36 moves out of the cabinet and the operator removes the sole from the tray and the mating lasted upper from the tray 64, assembles them on the left-hand press and depresses the foot treadle T² thereby initiating operation of the left-hand press. Depression of the treadle T² effects movement of the right-hand tray into the cabinet. From this point on the operator continues the operation by alternately depressing treadles T¹ and T².

The operating cycle as related above may be initiated by starting with switch PB³ instead of switch PB² which will merely reverse the sequence of operation.

It should be understood that the present disclosure is for the purpose of illustration only and that this invention includes all modifications and equivalents which fall within the scope of the appended claims.

40 I claim:

1. Apparatus for applying soles to lasted uppers comprising a two-station sole press, a two-station activator and a control circuit for synchronizing operation of the stations of the press and the activator, said control circuit embodying a starting switch operable to effect operation of one of the activators to move a sole into a position for activation of the adhesive thereon and at the end of a predetermined time to move it from said position for mounting with a lasted upper on one station of the sole press, a first treadle operable concomitantly to actuate said one station of the sole press and to effect operation of the other of the activators to move a sole into position for activation of adhesive there and at the end of a predetermined time to move it from the said position for mounting together with a lasted upper on the other station of the sole press, and a second treadle operable concomitantly to actuate said other station of the sole press and effect operation of the one of the activators to move a sole into position for activation of the adhesive thereon and at the end of a predetermined time to move it from said position, said first and second treadles being operable thereafter alternately to operate said one station of the sole press and said other activator, and said other station of the press and said one activator.

2. Apparatus for applying soles to lasted uppers comprising a two-station sole press and a two-station activator, said activator embodying a fixed heating grid and two sole supports mounted for movement alternately from a lateral position permitting placing of soles thereon to an operative position adjacent the grid for activation of the adhesive on said soles, a starting switch for effecting movement of one sole support to operative position and from operative position, a first treadle for effecting operation of one of the stations of the sole press and simultaneously effecting movement of the other sole support to operative position and from operative position, and a second treadle for effecting operation of the other station of

the sole press and simultaneously effecting movement of the one sole support to operative position and from operative position, said first and second treadles being operable thereafter alternately to effect operation of the one station and the other support and the other station and the one support respectively.

3. Apparatus according to claim 2, wherein there are two starting switches alternately usable to initiate operation of the apparatus with the sole support at the right side on which the right sole is mounted, or with the sole support at the left side on which the left sole is mounted.

4. Apparatus according to claim 2, wherein the movable sole supports are designed to receive and hold precoated right and left soles with their precoated surfaces parallel to the heating grid and wherein there is a fixed support above the movable supports designed to receive and hold the right and left lasted uppers to which the right and left soles are to be attached in the press.

5. Apparatus according to claim 4, wherein the fixed support is also heated for activating adhesive preapplied to the bottoms of the lasted uppers.

6. Apparatus according to claim 4, comprising resistance heating means supported beneath the fixed support, and means in the circuit for selectively controlling the amount of heat supplied to different portions of the resistance heating means.

7. Apparatus according to claim 6, wherein the resistance heating means embodies three units arranged to supply heat to areas of the support which would be overlain by the forepart, shank and heel end of lasted uppers resting on the support.

8. Apparatus according to claim 2, wherein the activator comprises a cabinet having an opening at one side, said heating grid being mounted in the cabinet above the side opening in a horizontal position, said sole supports comprising substantially flat trays, posts pivotally mounted at their lower ends in the cabinet, mounting at their upper ends said trays in spaced parallel relation to the heating grid, and pneumatic means connected to the posts operable to swing the posts about their pivots through said side opening to a position exteriorly of the cabinet in which the trays are inclined downwardly relative to the top of the cabinet.

9. Apparatus according to claim 2, wherein, the activator comprises a cabinet having an opening at one side, the movable sole supports are mounted within the cabinet for movement from within the cabinet through the side opening, and 5 there are motors supported in the cabinet connected to the movable sole supports and to the control circuit by means of which the sole supports are movable independently of each other from within the cabinet through the side opening, and means in the control circuit for causing said motors to move 10 both said sole supports from the cabinet through the side opening preparatory to commencing any sequence of operations.

10. Apparatus according to claim 8, wherein a flat table is mounted on the cabinet in a horizontal position below the 15 front opening and beneath the exterior positions of the trays.

11. Apparatus according to claim 8, wherein the tip of the cabinet contains an opening and a fixed tray is mounted thereon above the movable trays, said fixed tray being adapted to support a pair of lasted uppers for activation of adhesive on 20 the bottom surfaces thereof.

12. Apparatus according to claim 11, wherein there is a partition situated between the fixed and movable trays and there is resistance heating means supported beneath the fixed tray for effecting activation of the adhesive on lasted uppers resting 25 on the fixed tray.

13. Apparatus according to claim 8, wherein said fixed tray is substantially flat.

14. Apparatus according to claim 8, wherein said second 30 fixed tray has flat downwardly converging portions adapted to accommodate the bottom of an upper having a high heel.

15. Apparatus according to claim 8, wherein said fixed tray has articulated portions adjustable to adapt to the contour of the bottom of the lasted upper.

16. Apparatus according to claim 8, wherein a hinge pin 35 connecting the articulated portions of the tray is supported at its ends in the sidewalls of the cabinet for heightwise adjustment and the distal ends of the portions are pivotally supported for horizontal displacement relative to the hinge pin.

17. Apparatus according to claim 8, wherein the trays are 40 fixed to spindles telescopically mounted in the upper ends of the posts and are adjustable lengthwise therein.
